UNITED STATES PATENT OFFICE.

JOSEPH C. KENNEY, OF SCOTTDALE, PENNSYLVANIA.

MECHANISM-SUPPORT FOR TALKING-MACHINES.

1,336,842.

Specification of Letters Patent. Patented Apr. 13, 1920.

Application filed April 21, 1919. Serial No. 291,473.

To all whom it may concern:

Be it known that I, JOSEPH C. KENNEY, a citizen of the United States, residing at Scottdale, in the county of Westmoreland 5 and State of Pennsylvania, have invented certain new and useful Improvements in Mechanism-Supports for Talking-Machines, of which the following is a specification.

This invention relates to the subject of 10 acoustics, and has particular reference to a novel mechanism support for talking machine cabinets whereby the sounds produced are greatly clarified and generally improved in tone.

15 To this end the invention contemplates a cabinet construction, wherein the entire sound reproducing mechanism, including the motor and sound amplifying horn, is mounted upon a carrier which rests upon a resonant plate and has no other connection or 20 point of attachment with the surrounding cabinet or housing.

A further object of the invention is to 25 provide a simple and practical construction which is easily assembled and readily accessible for the purpose of making repairs or adjustments to the motor or other operating parts.

With the above and other objects in view 30 which will more readily appear as the description of the invention proceeds, the same consists in the novel construction, combination and arrangement of parts hereinafter more fully described, illustrated and claimed.

35 A preferred and practical embodiment of the invention is shown in the accompanying drawings, wherein:

The figure is a vertical sectional view of 40 a cabinet embodying the present improvements, portions of the cabinet being shown in elevation.

Although the present invention is susceptible of embodiment in various styles of talking machine cabinets there is shown in 45 the drawing an upright cabinet structure C which houses the entire sound producing mechanism and operating parts including the motor M. That is to say, the upper portion of the cabinet C houses a suitable car-

rier element which consists of a flat table 50 portion 1 having thereon the tone arm 2 and reproducer 3, and also the rotary platen 4 mounted on the motor driven spindle 5 above the top surface of the table, while the said 55 motor M, housed within a suitable casing, is

suspended from the under side thereof. This table is provided with the supporting members 6, and also carries the sound amplifying horn 7 which connects with the tone arm. Therefore, it will be apparent that 60 the entire sound reproducing unit is arranged upon the carrier which comprises the table 1 and supporting members 6, and as will be seen from the drawing the said table and all of its associated parts are absolutely 65 separate and independent from the casing C and have no connection at any point therewith.

Referring now more particularly to the 70 novel and distinctive feature of the invention it will be observed that the entire carrier is seated upon a resonant rest preferably a glass plate 8 the same being supported upon suitable felt, rubber or equivalent cushion elements 9 carried by the vertical corner posts or strips 10 in each corner of the cabinet. By reason of the fact that the entire sound reproducing mechanism is solely supported on this plate 8 the 75 sounds and tones reproduced by the playing mechanism are greatly amplified and clarified. And, because of the special mounting of the resonant plate on the corner strips 10, none of the vibrations of the casing parts 80 are transformed into audible sounds that 85 might otherwise be carried into the reproduction and distract from the rendition of the composition being played, and because of the mounting of the table-like mechanism supporting member on the center of 90 the resonant glass plate all of the sounds 95 reproduced are rendered more definite and distinct, thereby greatly improving the reproduction of the composition.

From the foregoing it will be apparent 95 that the present invention proposes to provide a simple and practical mechanism support which not only provides for conveniently carrying the entire sound producing apparatus, but also amplifies and clarifies the 100 sounds, so as to make the rendition of selections more attractive than with the usual cabinet construction.

I claim:

1. In a talking machine, the combination 105 with the cabinet, of a glass plate constituting a resonant rest, and a mechanism carrier supported solely on said glass plate.
2. In a talking machine, the combination 110 with the cabinet and operating mechanism,

of an interiorly arranged glass plate constituting a resonant rest, and a mechanism carrier entirely out of contact with the cabinet body and consisting of a table top for the mechanism, and depending supporting members or legs resting solely on said glass plate.

In testimony whereof I hereunto affix my signature in the presence of two witnesses.

JOSEPH C. KENNEY.
